GIRDLE

Samuel T. Metz, New York, N. Y., assignor to
 Treo Co. Inc., Jamaica, N. Y., a corporation of
 New York

Application December 8, 1949, Serial No. 131,711

2 Claims. (Cl. 2—36)

1

This invention relates to improvements in girdles and other horizontally expandable garments, and to an improved method of making such garments.

According to my invention, the body of the garment is made of material which has no inherent stiffness, such as an easily bendable and foldable knitted or woven fabric. Said body is preferably made wholly or in part of stretchable material, which is optionally and preferably elastic.

It has been proposed, as in United States Patent Nos. 1,019,339; 1,421,171; 1,797,890; 1,837,958; 2,334,529; 2,471,910 and Reissue No. 10,935, to apply a wavy reinforcing wire to various articles.

According to one embodiment of my invention, I make the body of the garment from a front panel and a rear panel, whose side edges are sewed to each other. These panels can be folded against each other in flat shape.

I then apply a springy or resilient wire to said panels at the top edge-portion of said body. This wire has an original straight shape, as one example. In any event, the original shape of said resilient wire is different from its final normal shape in which said wire is connected to said body.

In connecting the wire in its final normal shape to said body, I can use a sewing machine which has one or more needles which form zig-zag connecting stitches or other connecting stitches, which are optionally and preferably lock-stitches. This machine has a flat sewing plate which can be inserted between the panels.

I apply the original wire, which is preferably a covered wire, gradually to the body of the garment, while shifting said body laterally and axially relative to the sewing station, and while gradually and successively bending the original springy wire from its original shape, in order to fix the wire by means of said connecting stitches to the body, in the final normal shape of said wire. These connecting stitches overlie the wire.

When the connecting stitches have been formed close to the ends of the wire, I optionally and preferably connect the ends of the wire to each other by soldering or twisting or in any other suitable manner; and I complete the connecting stitches so that they overlie said connected ends of the wire. Said connected ends of the wire are preferably located at one of the side edges of the body of the garment.

The final normal shape of the wire when it is connected to the unstretched garment is a zig-zag shape, which has alternate top and bottom

points. The top points are located at or close to the top edge of the garment.

At each top point, the wire is preferably shaped to provide a downwardly curved portion, whose top face is convex. At each bottom point, the wire is preferably shaped to provide an upwardly curved portion, whose bottom face is convex.

At each panel, these curved portions are connected by legs which are wholly or substantially straight and vertical. These vertical resilient legs maintain the top-portions of the front and back of the garment in the desired normal shape, which is substantially flat when the garment is off the body of the user. This prevents the top edge-portion of the garment from rolling down, and makes it unnecessary to provide the usual bones or stays or other stiffening devices.

At each edge of each panel, a side branch of the springy wire is provided. This side branch is upwardly curved at its bottom. These two side branches have sufficient resilience to normally transversely space the top edge-portions of the front and back of the body from each other. This effect is assisted by the curved shape of the wire at its top ends.

By applying light pressure, the entire garment can be folded flat with the inner faces of the panels abutting each other, and the garment can be packed and shipped in such flat shape.

When the garment is horizontally expanded at its circumferentially continuous top, the resilient wire bends and expands in unison with the garment, with a reduction in curvature of said curved portions. These curved portions retain their curved shape when the garment is horizontally expanded to its limit of expansion. The main decrease in curvature is at the top curved portions. The decrease of curvature of the bottom curved portions may be very slight and even negligible. This effect is produced or assisted by providing suitable vertical spacing between said top and bottom points of the wire.

The body of the garment may be made wholly of elastic fabric which is elastic both vertically and horizontally. However, the invention is not limited to such construction of the body, and it is applicable to any body which is horizontally either extensible or elastic. It is well-known to make the bodies of these garments with panels and parts which have either one-way stretch or two-way stretch, and also to provide non-stretchable inserts and parts in these garments; so that these details require no illustration.

Other objects and features and advantages of my invention are set forth in the annexed de-

scription and drawings, which illustrate a preferred embodiment of my invention.

Fig. 1 is a front elevation of the garment, with the top reinforcing strip removed, the bottom edge of said reinforcing strip being indicated by a broken horizontal line. The resilient wire is shown in its normal shape and the garment is shown in normal non-expanded shape;

Fig. 2 is a rear elevation of Fig. 1;

Fig. 3 is a section on the line 3—3 of Fig. 1;

Fig. 4 is a front elevation on the line 4—4 of Fig. 1, showing the top reinforcing strip. The resilient wire is shown in its normal non-extended shape; and

Fig. 5 is similar to Fig. 4, showing the garment horizontally expanded from its normal non-expanded shape of Figs. 1, 2 and 4, and showing the corresponding bending and horizontal extension of the springy wire.

In this embodiment, the body of the garment consists of a front panel 10 and a rear panel 11, whose side edges are stitched to each other by side stitches 12. In this embodiment, the panels 10 and 11 are made wholly of two-way elastic knitted material, which is elastic in the horizontal and vertical directions, and also in directions diagonal to said horizontal and vertical directions. As above-noted, the invention is not limited to this feature.

The body of the garment has a top edge 18 and a bottom edge 14. Garters 13 are fixed to bottom edge 14.

The covered springy wire 15 has top points 17, at or close to the top edge 18 of the body of the garment.

In this embodiment, the wire has a downwardly curved portion at each top point 17.

At each panel 10 and 11, the wire 15 has legs which extend downwardly from said downwardly curved top portions to the ends of the bottom, upwardly curved portions of the wire. These legs are substantially straight and vertical.

At each panel 10 and 11, the wire has two bottom points 17a, and an intermediate bottom point 17c, which is lower than points 17a. As shown in Figs. 1 and 2, the wire 15 has the same shape and dimensions at the front and rear panels. If the garment is folded flat, with the inner faces of panels 10 and 11 abutting each other, the respective parts of the wire at said panels will coincide.

The wire 15 is located at the outer faces of the panels 10 and 11, and said wire is fixed to the body of the garment by the connecting stitches 16.

A branch Ls of the wire 15 is provided at each side edge of the garment. Each branch Ls has an upwardly curved bottom portion, whose bottom point is at the level of bottom point 17c or below bottom point 17c.

Each side branch Ls is symmetrical relative to the respective side-edge of the body. These side branches Ls are identical.

After the wire 15 has been connected, optionally and preferably in endless form to the body, a continuous elastic strip 19 is sewed around the circumferentially continuous top-portion of the garment by stitches 20. These stitches 20 and the stitches 16 are preferably stretchable. The reinforcing strip 20 is located in front of the top curved portions of the wire 15. It is not connected to said top curved portions.

The drawings are substantially to scale, and reference is made thereto for further disclosure.

As one practical illustration, the height of each

side edge of the garment is approximately 13 inches; the vertical distance between top edge 18 and each bottom point 17a is approximately 3 inches; the vertical distance between top edge 18 and each median point 17c is approximately 3.5 inches; the horizontal distance between the vertical straight legs of the wire at each panel is approximately 1.25 inches to 1.50 inches.

This provides sufficient height for the wire between its respective alternate top and bottom points, to prevent the top edge-portion of the garment from rolling down. The garment is worn in the usual manner, so that it extends above the hips of the wearer and it encloses the hips.

The stretchable material of the garment is preferably unstretched or substantially unstretched while the wire 15 is sewed thereto. The resilience of the wire exerts only slight stretching force on the material of the garment. If the connecting stitches 16 are removed from the wire 15, between the ends of a downwardly curved part thereof, the released part of the wire 15 will expand, so that the horizontal distance between its legs is increased to about 2 inches.

The improved garment has a waist-portion or waist-zone, and a hip-portion or hip-zone.

If desired, the wire 15 may be confined wholly to the waist-portion of the garment.

As an alternative, the wire 15 may extend partially into the hip-portion. Thus all the bottom points of wire 15 may be located in the hip-portion, and all the top points 17 of wire 15 may be located in the waist-portion.

As another alternative, only some of the bottom points of wire 15 may be located in the hip-portion, and the other bottom points of wire 15 may be located in the waist-portion.

Thus, the points 17a may be located in the waist-portion and the respective front and rear points 17c and the bottom points of the side branches Ls may be located in the hip-portion.

Also, only the bottom points of side branches Ls may be located in the hip-portion.

The invention is therefore not limited to the vertical distances between the top and bottom points of wire 15 which are stated in the specific example.

The garment may also be of the "pantie" type and it may have an extension above the wire 15.

When the wire 15 is held under flexure by the connecting stitches 16 in its normal non-expanded shape shown in Figs. 1, 2 and 4, the flexure of wire 15 is insufficient to produce any wrinkles or pleats in the knitted or woven fabric or other material of the body of the garment, when said body is in its normal unstretched shape shown in Figs. 1, 2 and 4. Hence said material remains smooth, and its stretch is not affected by the bent wire 15.

I have described a preferred embodiment of my invention, but numerous changes and omissions and substitutions and additions can be made without departing from the scope of my invention.

I claim:

1. A form-fitting girdle garment adapted for substantially-flat folding, and comprising a flexible, stretchable body, said body having a front portion, a rear portion, and areas of connection between said portions, a flexible sinuous wire having spaced legs joined by alternate top and bottom arcuate sections, said wire extending within and throughout the upper area of said body, overlay threads extending through the girdle.

body and over said wire, said wire being adapted for substantially-flat folding of the girdle and being restrained to said sinuous form by said overlay threads, the said top arcuate sections thereof being close to the top edge of said body and operative to prevent said waist portion from rolling down.

2. A form-fitting girdle garment adapted for substantially-flat folding, and comprising a flexible, stretchable body, said body having a front portion, a rear portion, and areas of connection between said portions, a flexible sinuous wire having spaced legs joined by alternate top and bottom arcuate sections, those legs which are joined by bottom arcuate sections at the center of the girdle body and at the areas of connection between the front and back portions being relatively long, said wire extending within and throughout the upper area of said body, overlay threads extending through the girdle body and over said wire, said wire being adapted for substantially-flat folding of the girdle and being

restrained to said sinuous form by said overlay threads, the wire legs being substantially straight and the said top arcuate sections thereof being close to the top edge of said body and operative to prevent said waist portion from rolling down.
